(57) **CLAIM**

What is claimed is the ornamental design for a distance measuring device, as shown and described.

DESCRIPTION

FIG. 1 is a top plan view of a distance measuring device showing the new design;

FIG. 2 is a bottom plan view thereof;

FIG. 3 is a left side elevational view thereof;

FIG. 4 is a right side elevational view thereof;

FIG. 5 is a front side elevational view thereof;

FIG. 6 is a rear side elevational view thereof; and,

FIG. 7 is a perspective view thereof.

Within the figures any surface shading is used solely to show the character or contour of the surfaces represented.
